UNITED STATES PATENT OFFICE.

WILLIAM GEO. PERRY, OF PHILADELPHIA, PENNSYLVANIA.

DESIGN FOR A GAME-BOARD.

SPECIFICATION forming part of Design No. 29,748, dated November 29, 1898.

Application filed November 7, 1898. Serial No. 695,795. Term of patent 7 years.

To all whom it may concern:

Be it known that I, WILLIAM GEO. PERRY, a subject of the Queen of Great Britain, residing at the city of Philadelphia, in the county 5 of Philadelphia and State of Pennsylvania, have invented and produced a new and original Design for Game-Boards, of which the following is a specification.

In the accompanying drawing, in perspective, is illustrated a game-board embodying the particular features of design of my said invention.

The leading feature of my said design consists of the shape or configuration of the 15 board, which in outline resembles a gridiron, the substantially rectangular handle of which extends in a plane angular with respect to the horizontal plane of the square-shaped body and said handle being formed at its free 20 end into a downwardly-depending semispherical hollow portion *h*.

Referring to the drawing, *a* represents the body or main field of the board, which is substantially square in outline and is supported 25 in a horizontal plane upon the legs or supports *b*. The body or main field *a* is almost entirely inclosed by an upwardly-projecting

rim *d* at right angles to the body or field *a*, but has an opening *e* in said rim at the point where the handle or auxiliary field *f* joins 30 said body or main field *a*. This handle or auxiliary field *f* is substantially rectangular in outline and projects from the body *a* at an angle to the horizontal plane of said body. The rim *d* of the field *a* is extended 35 along the sides of the handle *f* and around its free end *g*, at which point *g* the rim *d* is curved. The free end *g* of the handle *f* is formed into a downwardly-depending semispherical hollow portion *h*. The handle *f* is supported in 40 its angular relationship to the body *a* by a leg or support *k*.

Having thus described my invention, what I claim as new, and desire to secure by Letters Patent, is—

The design for a game-board, substantially as herein shown and described.

In testimony whereof I have hereunto set my signature in the presence of two subscribing witnesses.

WM. GEO. PERRY.
